UNITED STATES PATENT OFFICE.

FRANZ MARSHALL McCONNELL, OF LONGVIEW, TEXAS.

NASAL EXPANDER.

1,014,076.

Specification of Letters Patent.

Patented Jan. 9, 1912.

Application filed January 7, 1910. Serial No. 536,919.

To all whom it may concern:

Be it known that I, FRANZ M. McCONNELL, a citizen of the United States, residing at Longview, in the county of Gregg and State of Texas, have invented a new and useful Nasal Expander; and I do hereby declare the following to be a full, clear, and exact description of the invention, such as will enable others skilled in the art to 10 which it appertains to make and use the same.

The invention relates to a nasal expander, and has for its object to provide a device of this character, which is designed to prevent the nasal passages from collapsing or contracting, or closing, particularly while the patient is asleep, but it will be understood that this invention can be used to advantage under some circumstances, during 20 waking as well as sleeping hours.

In the drawings:—Figure 1 is a perspective view, showing my invention applied to the nose. Fig. 2 is a side elevation of the device. Fig. 3 is a top plan view. Fig. 4 25 is a detail perspective view, on an enlarged scale, showing the spring applied to one of the levers.

Referring to the drawings, 1 and 2 designate the two wings of my invention, the 30 inner ends of which are approximately circular, and which are designed to force the nasal passages open. The two wings are connected together by a bridge member 3, on each side of which is a lever 4 provided 35 with a flattened portion 5 adapted to be gripped when operating the lever. The levers are mounted on pivots 6 and the inner end of each lever is pressed inwardly against the cartilage of the nose by means 40 of a spring 7, as clearly shown on an enlarged scale in Fig. 4 of the drawings. The inner ends of these levers 4 are also flattened as shown at 8 in Fig. 3 of the drawings. These flattened ends which press 45 against the cartilage of the nose, are provided with openings 9. These openings 9 are for the purpose of permitting a protrusion therethrough which serves to some extent to lock the device in engagement with 50 the cartilage of the patient. This effectively prevents displacement of the device. When it is desired to remove the nasal expander,

the flattened portion 5 of the levers 4 are pressed inwardly or together, and thus the device is released from the nose.

It will be seen that my invention is simple, inexpensive and durable, and is certain to prove of service in catarrh, and other ailments caused by diminishing or contracting the nasal passages.

What is claimed is:—

1. A nasal expander, comprising a bridge member having a central curved portion to engage the terminal of a nose cartilage and provided with integral disk portions upon 65 each side of the curved central portion, said disk portions having laterally extending integral members arranged approximately parallel to one another having loops, said members being of sufficient resiliency as to 70 bear against the inner surfaces of the outer side walls of a nose to spread the nasal passages, screw members threaded into the disk portions and projecting downwardly therefrom, levers having disk members pivoted 75 upon the screw members, coil springs coiled about the screw members and interposed between the heads of the screw members and the disk members of the levers, said springs having one of their ends engaging the 80 laterally extending integral members, while the other ends bear against the inner free portions of the levers, to hold said portions against the cartilage of the nose, said free portions terminating in loops, as and for the 85 purpose specified.

2. A nasal expander, comprising a bridge portion, extending transversely of the nose, a wing connected with each side of said bridge and formed integrally therewith, a 90 lever pivotally mounted at the junction of each wing and bridge, the inner ends of said levers being flattened and provided with an opening in the flattened portion for enabling said levers to lock themselves in engagement 95 with the cartilage of a patient's nose.

3. In a nasal expander, a bridge, wings connected with said bridge, and designed to be inserted in the nasal passages, spring press levers, adapted to extend into the nasal 100 passages, for clamping the nasal expander to the patient's nose.

4. A device of the class described comprising a bridge, wings connected with each

end of said bridge and adapted to expand the nasal passages, spring press levers having flattened inner ends, said flattened portions being provided with openings whereby 5 said levers effectively lock said expander in engagement with the cartilage of the patient's nose.

In testimony whereof I have signed my name to this specification in the presence of two subscribing witnesses.

FRANZ MARSHALL McCONNELL.
